US0D1037468S

(12) **United States Design Patent** (10) **Patent No.:** **US D1,037,468 S**
(45) **Date of Patent:** **** Jul. 30, 2024**

(54) **LED PHOTOTHERAPY DEVICE**

(71) Applicant: **Hui Huang**, Sichuan (CN)

(72) Inventor: **Jun Long Liu**, Guangdong (CN)

(**) Term: **15 Years**

(21) Appl. No.: **29/845,340**

(22) Filed: **Jul. 6, 2022**

(30) **Foreign Application Priority Data**

May 31, 2022 (CN) 202230330652.7

(51) **LOC (14) Cl.** **24-01**

(52) **U.S. Cl.**

USPC **D24/200**; D24/209

(58) **Field of Classification Search**

(57) **CLAIM**

The ornamental design for a LED phototherapy device, as shown and described.

DESCRIPTION

FIG. 1 is a front elevational view of a LED phototherapy device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof in a use condition; and,

FIG. 10 is a fourth perspective view thereof in a use condition.

1 Claim, 10 Drawing Sheets
